UNITED STATES PATENT OFFICE

141,814

DESIGN FOR A TEAPOT

Rudolph Ganz, Zanesville, Ohio, assignor to Shawnee Pottery Company, Zanesville, Ohio, a corporation of Ohio

Application May 11, 1945, Serial No. 119,494

Term of patent 14 years

(Cl. D44—26)

To all whom it may concern:

Be it known that I, Rudolph Ganz, a citizen of the United States of America and a resident of the city of Zanesville in the State of Ohio, have invented a new, original, and ornamental Design for Teapot, of which the following is a specification, reference being had to the accompanying drawings, forming a part thereof, wherein

Fig. 1 is a front elevational view of a teapot
showing my new design;

Fig. 2 is a rear elevational view thereof;
Figs. 3 and 4 are elevational views of the tea-
pot showing the handle side and the spout side, respectively; and

Fig. 5 is a top plan view of the teapot.

I claim:

The ornamental design for a teapot, as shown.
RUDOLPH GANZ.
